DECORTICATING OF FLAX AND OTHER
BAST FIBERS

John Thomson, Paisley, Scotland

Application April 22, 1942, Serial No. 440,033
In Great Britain May 2, 1941

8 Claims. (Cl. 19—11)

This invention relates to the decorticating of flax, whether retted or green, and other bast fibers. In this specification and in the appended claims the term "straw" is used to designate the flax and other stalks which are decorticated.

More particularly the invention relates to a machine in operation of which opposite ends of a length of straw, arranged in a sheet or layer, are gripped and a relative reciprocatory motion between the gripping means is effected so that the length of straw is bent first in one direction and then in the opposite direction and in this way the straw is decorticated.

An object of the invention is to provide an improved machine for decorticating straw by feeding the straw through a decorticating zone in a continuous supply spread out in a wide layer and by repeatedly bending the straw at said zone throughout practically the entire length of every stalk, no matter how short, in alternately opposite directions.

Another object of the present invention is to provide an improved machine in which the work of feeding in the straw and the subsequent decortication of it will follow one another as a continuous operation—that is, without interruption by stoppage of the machine.

Another object of the invention is to provide a machine in which the gripping means are timed to open and close in such relation to the relative reciprocatory motion that the length of straw is pulled into position in a controlled manner for decortication by the action of the machine.

Another object of the invention is to provide feed means to assist the gripping means in their work of pulling the straw into the decortication position.

Another object of the invention is to provide means for withdrawing the straw length by length from the grippers following each decortication operation.

Other objects of the invention will be apparent from the following specification and appended claims.

The invention is illustrated by the accompanying drawings, in which:

Fig. 1 is a diagram showing the straw grippers and associated means for feeding-in the straw to be decorticated and for withdrawing it after decortication.

Fig. 2 is a diagram of means for opening and closing one of the grippers.

Fig. 3 is a similar diagram of means for re-

ciprocating and means for opening and closing the other gripper.

Figs. 4 to 8 are a series of diagrams drawn to a smaller scale than Fig. 1 and showing the grippers and associated means in different positions in the cycle of operations.

Figs. 9 to 13 show a machine which operates in accordance with the principles illustrated by the diagrams Figs. 1 to 8. Figs. 9 to 13 are drawn to a small scale and various of the parts shown are conventionally represented. Of these figures, Fig. 9 is an end elevation of the machine, Fig. 10 is a plan with upper parts removed for clearness, Fig. 11 is a section on line XI—XI of Fig. 10, and Figs. 12 and 13 are fragmentary sectional elevations approximately on lines XII and XIII, respectively, of Fig. 10.

Throughout the several figures of the drawings, similar parts or corresponding parts are denoted by the same reference characters.

Referring to Fig. 1, the parts therein shown comprise: two pairs of superimposed complementary gripping blocks, the blocks of the first pair being denoted 14 and 15 and the blocks of the second pair being denoted 16 and 17; an assembly of lead-bands, namely a single lower feed band 18 and upper and lower withdrawal bands 19 and 20; and a pair of rollers 21, 22 housed and journaled in the blocks 16, 17 and adapted to supplement the action of lead-bands 19, 20. A layer of straw is denoted by S. The blocks 14, 15, are spaced apart from the blocks 16, 17 to provide a gap G which is just large enough to afford little more than a working clearance for the decorticating operation, which takes place in the gap. It will be seen that the straw S occupies a horizontal plane where it passes through each pair of gripper blocks and that the gap G extends vertically, i. e. transversely of said plane.

The blocks 14, 15 are at the feed side of the gap. They have facings 14A, 15A, which are shaped to widen the gap as it recedes upwards and downwards from the gripping plane of each pair of blocks. The blocks 16, 17 have face plates 16A, 17A, which close the housing spaces for the rollers 21, 22. The lead-bands may be made of linen. The single feed band 18 passes between the first blocks 14, 15, whereas the upper and lower withdrawal bands 19, 17 pass from the gap G between the second blocks 16, 17 and between the rollers 21, 22. These are smooth steel rollers.

The lower block 15 of the first pair is a permanently stationary fixture, and the complemen-

tary upper block 14 is also stationary except for a temporary opening and closing motion described hereinafter. That is to say, the first gripper constituted by the blocks 14, 15 is supported in a stationary location. On the other hand, the lower block 17 of the second pair is a reciprocatory element, and the complementary upper block 16 reciprocates in unison with it except for a temporary superimposed opening and closing motion. That is to say, the second gripper constituted by the blocks 16, 17 is reciprocatory. Figs. 2 and 3 show how the opening and closing motions and the reciprocatory motion are obtainable.

As shown in Fig. 2, the block 14 has fulcrumed on it a bellcrank lever 23 which is connected by a wire 24, a lever 25 and a wire 26 passing over a pulley 27 to a cam-lever 28, which co-operates with a cam 29 on a slow-speed shaft 30 driven by gears 31, 32 from a main driving shaft 33. The levers 25 and 28, the pulley 27 and the shafts 30 and 33 are all turnable or rotatable about stationary axes. One arm of the lever 23 presses down on a projection 34 on the stationary lower block 15. A spring 35, with a stationary anchorage 36, presses the upper block 14 towards the lower block, and stationary guides 37 serve for the guidance of the block 14. In operation, when the hump of the cam 29 makes contact with the lever 28, the lever 23 is pulled to force the block 14 upwards against the pressure of spring 35. Thus, for a short period in one of every series of revolutions of the driving shaft 33 (say in every eighth revolution) the gripper 14, 15 is opened. When the cam hump passes the lever 28, the upper block 14 is forced by the spring action to close again on the lower block 15.

As shown in Fig. 3, the lower block 17 is reciprocated between stationary guides 38 for both blocks 16, 17, by an eccentric 39 which is on the driving shaft 33 and which acts through a connection 40 on the block 17. The opening and closing motion of the upper block is effected by cam-action through parts 23-36 similar to those already described with reference to Fig. 2 except that the fulcrum of lever 25 and the anchorage 36 are not stationary but are provided on brackets 41 and 42 respectively secured to the blocks 16 and 17.

Fig. 1 shows the parts in what may be conveniently regarded, for the purposes of explanation, as the starting position of the cycle of operations. In this position, the gripping surfaces of both pairs of blocks are co-planar and both pairs are closed on the straw S. Fig. 4 shows the parts which are more important for the purpose of pictorial representation in the same position, less important parts being omitted from Fig. 4 and the corresponding Figs. 5 to 8 for clearness; and the cycle of operations will now be described with reference to these figures.

In the Fig. 4 position, the second gripper assembly (of which only the faces 16A, 17A and rollers 21, 22 are shown) is descending in its reciprocatory motion. Next, the first gripper 14, 15 is temporarily opened, its upper block 14 being lifted by the associated cam-mechanism (Fig. 2). The full open position of the first gripper is shown in Fig. 5. The first gripper closes again by the time that the second gripper reaches the bottom of its descent, as Fig. 6 shows. During the short period that the first gripper is open, straw S is pushed through it by the momentarily advancing lead-band 18 (Fig. 1) and a length of the straw is pulled into the gap G by the de-

scending second gripper. In the Fig. 6 position, the pulled-in length of straw is gripped at opposite ends by the grippers. The motion from Fig. 5 to Fig. 6 is the first half-stroke of the cycle, and the decorticating action now starts. This action is effected by the reciprocating second gripper. Fig. 7 shows the second gripper at the top of its ascent. In the up-and-down motion between the limits shown in Figs. 6 and 7, the central plane of this motion being at the level where the two grippers are in horizontal alignment, the length of straw is rapidly bent in alternately opposite directions within the confined space of the gap G. The straw is not only sharply bent to-and-fro, but is also rubbed by the walls of the gap. There may be about seven down-strokes and eight up-strokes imparted to the second gripper in order to perform decortication completely. At the end of the decorticating action, the second gripper is at the top of its up stroke, as represented by Fig. 7. During the first half of its next down-stroke (which is the last half-stroke of the cycle) the second gripper is opened and closed again by the associated cam-mechanism (Fig. 3). The second gripper is shown full open in Fig. 8 and is shown closed again in Fig. 4. Whilst the second gripper is open, the lead-bands 19, 20 are momentarily advanced and the rollers 21, 22 are momentarily rotated to withdraw the decorticated length of straw from the gap.

Thus it will be seen that in a cycle of say sixteen strokes (or eight reciprocations) of the second gripper, the time taken by one of these strokes is utilised partly for withdrawing a decorticated length of straw and partly for bringing in a new length, and the remaining strokes are all devoted to the decorticating action.

In the foregoing description, the layer of straw S has been assumed to extend from the feed-band 18 and across the decortication gap G to the withdrawal bands 19, 20. At the commencement of decorticating a supply of straw S, the straw is merely placed upon the feed-band 18 and the machine is started. The leading end of the straw is entered step-by-step through the first gripper by the stepwise advancing feed-band. The material is pushed against the bands 19, 20, which both form in effect one wall of the gap. In each upstroke of the blocks 16 and 17 constituting the second gripper, the ungripped end of the straw is bent upwards by the upgoing second gripper, so that at the top of its upstroke the straw is lying against the band 20 on the face of the lower block plate 17A. Assume that the second gripper is due to open during the first half of its next downstroke, as Fig. 8 illustrates. As the second gripper descends the blocks 16, 17 constituting its jaws open and the rollers 21, 22 are rotated to advance the bands 19, 20, with the result that the band 20 now travelling upwards relative to the block 17 maintains the straw end bent upwards until eventually the opening between the blocks 16, 17 reaches the straw end, and the bands 19, 20 as they move between the now closing blocks 16, 17 co-operate to draw the straw end between themselves, so that said end is gripped. This action of gripping the end of a batch of straw fed between the blocks 14, 15 of the first gripper takes place surely and speedily and automatically.

The foregoing description of the main parts according to Figs. 1 to 8 and of their cycle of operation applies fully to the machine according to Figs. 9 to 13. These figures serve chiefly to

show the machine as a whole and to give particulars of the mechanism not shown in the previous figures, namely Figs. 1 to 8, for operating the moving parts.

Referring to Figs. 9 to 13, the frame of the machine comprises two gables 43, 44 by which most of the working parts are supported and between which the gripper blocks extend, the guides 37, 38 for the ends of the blocks 14, 16 and 17 being provided in these gables, as Figs. 9, 12 and 13 indicate. The block 15 is a stationary fixture on the gables 43, 44. The guides 38 constrain the movable gripper 16, 17 to rectilinear motion transverse to the horizontal plane of the straw S throughout the operation of the machine.

The main driving shaft 33 is driven at one or both ends by say a pulley or pulleys 45 and the connections between said shaft and the cam-shafts 30 comprise toothed gear wheels 32, 31 of gear ratio 8:1. A set of these gear wheels may be provided at each end of the machine, as shown.

The lead-bands 18, 19 and 20 are operatively connected to the gear wheels 31 from which they receive their momentary advance motions in the operation of the machine whilst the respective grippers are open for the feed-in and withdrawal of the straw. These three bands are shown in dotted lines in Figs. 10 and 11.

As shown, the feed band 18 is led around a series of rollers comprising: a roller 46 (Fig. 11) journaled in stationary brackets (not shown) beyond the end of the gables 43, 44; a pair of band-tensioning rollers 47 journaled on a stationary beam 47A (Fig. 13) below the gables and acted upon by spring-tensioning devices 48 (conventionally represented); and three pairs of rollers 49, journaled in the gables 43, 44, the rollers of each of these pairs gripping the upper straw-receiving stretch of the band 18 at the nips between them. The upper rollers 49 are the only ones in the series which are positively driven. They are connected by a driving chain 50 to a train of gears 51, the endmost of which is on the same shaft as a pinion 52 (see Fig. 9) which receives a small turn from an adjustable striker 53 on the adjacent gear wheel 31 once in each revolution of that gear wheel. That is to say, the feed-band 18 receives its momentary advance motion once in every eight revolutions of the main driving shaft 33.

Each of the withdrawal bands is led around a series of rollers comprising: a band-tensioning roller 54 journaled in the gables 43, 44, the tensioning devices 55 being represented conventionally in Fig. 9; one of a pair of co-operating rollers 56 which are journaled in the gables and which nip both bands between them at the straw-engaging stretch leading from the rollers 21, 22 (see also Fig. 1); and two rollers 57 journaled in brackets 58 secured to the respective gripper block 16 or 17 and acted upon by band-tensioning devices 59 conventionally represented in Fig. 12. There is a chain drive 60 between the shaft of a driving pinion 61 and one of the rollers 54; and there is another chain drive 62, through an idler gear 63, between these two rollers. The pinion 61 is operated by an adjustable striker 64 in the same way as the pinion 52 for the feed band 18. Thus, the withdrawal bands 19, 20 also receive their momentary advance motion once in every eight revolutions of the main driving shaft 33.

As Fig. 9 indicates, the driving pinion 61 for the withdrawal bands is actuated slightly in advance

of the pinion 52 for the feed-band. This is because the second gripper 16, 17 opens slightly in advance of the first gripper 14, 15 during that stroke of the second gripper—namely, during that half-revolution of the main shaft 33—devoted to the advance motions of the straw.

The tensioning devices applied to the various lead-band rollers allow the respective lead-bands to follow up-and-down movement due to the passage of the straw and due to the reciprocatory motion of the second gripper 16, 17. At the delivery zone of the withdrawal lead-bands 19, 20, a table (not shown) may be provided to receive the decorticated straw as it issues from said lead-bands.

It will be clear that the method of decorticating applied by the operation of the machine hereinbefore described consists in effecting a reciprocatory motion between the gripped ends of a length of straw so as to bend the length of straw repeatedly in alternately opposite directions until it is decorticated. In the following claims the foregoing method is referred to for brevity as a decorticating action.

I claim:

1. A decorticating machine comprising a stationary gripper, means for opening said gripper periodically, a movable gripper spaced from said stationary gripper to provide a decorticating gap, mechanism for reciprocating said movable gripper to perform a decorticating action, means for opening said movable gripper periodically as it reciprocates, straw-feed means leading to said stationary gripper, straw-withdrawal means leading from said gap through said movable gripper, mechanism operatively connected to said stationary-gripper-opening means and timed for operation of said straw-feed means to feed straw to be decorticated through said stationary gripper and push said straw across said gap when said stationary gripper is opened and while said movable gripper is closed, and mechanism operatively connected to said movable-gripper-opening means and timed for operation of said straw-withdrawal means to pull decorticated straw from said gap and through said movable gripper when it is opened and while said stationary gripper is closed.

2. A decorticating machine as claimed by claim 1 including also guide means constraining said movable gripper to a rectilinear movement throughout the operation of the machine.

3. A decorticating machine as claimed by claim 1 in which said stationary gripper is arranged at the level of said straw-feed means, said movable gripper reciprocates between limits above and below said level, and said straw-feed operating mechanism is timed to push in straw while said movable gripper is moving from said level towards one of said limits.

4. A decorticating machine as claimed by claim 1 in which said movable gripper comprises a pair of cooperating blocks and in which said straw-withdrawal means comprises endless bands forming a wall of said gap and passing between said blocks and roller means leading said bands to convey decorticated straw from said gap between said blocks.

5. A decorticating machine as claimed by claim 1 in which said stationary gripper comprises a pair of cooperating blocks and in which said straw-feed means comprises a flat conveyor band passing between said blocks.

6. A decorticating machine comprising a first gripper, means for opening said gripper periodi-

cally, a second gripper spaced from said first gripper to provide a decorticating gap, mechanism for effecting a relative reciprocatory motion between said grippers to perform a decorticating action, means for opening said second gripper periodically, straw-feed means leading to said first gripper, straw-withdrawal means leading from said gap through said second gripper, mechanism connected to said first-gripper-opening means and timed for operation of said straw-feed means to feed straw to be decorticated through said first gripper and across said gap when said first gripper is opened and while said second gripper is closed, and mechanism connected to said second-gripper-opening means and timed for operation of said straw-withdrawal means to withdraw decorticated straw from said

gap and through said second gripper when it is opened and while said first gripper is closed.

7. A decorticating machine as claimed by claim 6 in which said second gripper comprises a pair of cooperating blocks, and in which said straw-withdrawal means comprises endless bands forming a wall of said gap and passing between said blocks and roller means leading said bands to convey decorticated straw from said gap between said blocks.

8. A decorticating machine as claimed by claim 6 in which said first gripper comprises a pair of cooperating blocks and in which said straw-feed means comprises a flat conveyor band passing between said blocks.

JOHN THOMSON.
